UNITED STATES PATENT OFFICE.

CHARLES COTTON, OF OLEAN, NEW YORK.

WAGON-RACK.

SPECIFICATION forming part of Letters Patent No. 289,234, dated November 27, 1883.

Application filed August 8, 1883. (No model.)

To all whom it may concern:

Be it known that I, CHARLES COTTON, a citizen of the United States, residing at Olean, in the county of Cattaraugus and State of New York, have invented a new and useful Hay, Grain, or Stock Rack, of which the following is a specification, reference being had to the accompanying drawings.

This invention relates to certain new and useful improvements in combined hay and stock racks; and it has for its object to provide a rack which shall be capable of separately performing the functions of either of these devices.

With these ends in view my invention consists of a platform mounted upon a series of transverse beams secured to longitudinal beams by means of tenons and dowel-pins, the said platform and cross-beams being transversely slotted, in which slots are fitted curved standards connected together by means of longitudinal rails or strips, a ladder being secured to one end of the platform, and a cross-bar, against which the ladder abuts, and the forward standards, whereby a hay-rack is constituted. When it is desired to convert the device into a stock-rack, the sides are removed and the standards on each side placed in mortises formed in the other side, whereby the curvature of the standards is reversed, end pieces are fitted between the sides, and a cover consisting of two or more longitudinal strips connected together by means of bars is placed upon the upper rails, all of which will more fully hereinafter appear.

In the accompanying drawings, forming a part of this specification, and on which like letters of reference indicate corresponding parts, Figure 1 represents an end elevation of my invention, showing the hay-rack; Fig. 2, a perspective view, showing the same when constituting a stock-rack; and Fig. 3, a cross-section showing the manner of connecting the standards with the transverse beams and the platform.

The letter A indicates a platform, the same being constructed, preferably, of wood, and mounted upon a series of transverse bars, A', the ends of which bars are provided with tenons.

The letter A² indicates longitudinal side beams provided with mortises, which register

with and which are adapted to receive the tenons on the ends of the transverse bars, dowel-pins being employed and driven through the tenons to hold the parts together.

The letter A³ refers to a series of curved standards, the lower ends of which are provided with tenons, which fit snugly into mortises A⁴, formed in the platform and the transverse bars A'. The mortises A⁴ are inclined, and the upper inner edges of the longitudinal beams A² are notched, so as to receive the standards A³ and allow them to incline outwardly, so as to increase the capacity of the hay-rack.

It will be seen by reference to Fig. 1 that the sides of the rack have been changed—that is to say, that the left side has been placed in the mortises of the right side, and the right side placed in the mortises of the left side, whereby the curvature of the standards A³ is reversed and the capacity and strength of the rack increased.

To the standards A³ are secured a series of rails or bars, B, by means of screws, bolts, or other fastening devices, the said rails constituting the sides of the rack. Near one end of the platform a frame or ladder is pivotally connected with the inner sides of the longitudinal beams A², the said ladder consisting of two bars, B', converging toward their upper ends, and connected together by cross-pieces B² and B². The upper bars are mortised, and the pieces tenoned for this purpose, the protruding ends of the tenons being provided with dowel-pins, whereby the parts are securely held together.

In order to afford a rest for the ladder, I provide a brace, C, which is bolted to the two forward standards immediately in front of the ladder.

When it is desired to convert my hay-rack into a stock-rack, the sides are changed from one set of mortises to the other, placed in an upright position, and the cover applied, as seen in Fig. 2, the said cover consisting of a series of transverse bars, C', having their sides near their ends notched, so as to fit over the edges of the upper rails B, two or more longitudinal rails, C², being secured thereto by means of bolts or screws.

The letter D indicates the end pieces of the rack when used as a stock-rack, the said pieces

being notched on their edges near their upper ends, so as to receive the two upper rails B. The end transverse beams C' are provided with apertures, through which pass vertical bolts E, the said bolts being also passed through the platform, and provided on their lower ends with screw-threads to receive nuts, whereby the cover is firmly held down upon the upper rail and secured in its place. I also provide at one end of the rack the transverse bolt E', which passes through two of the longitudinal rails B, and is provided with a nut, so as to draw the sides toward each other.

In order to prevent the displacement of the hay-rack upon the wagon-truck, I provide the longitudinal side bars, A², with cleats, between the ends of which the bolster-standards are adapted to fit. I also provide the side bars with metallic plates, which receive the abrasive action of the forward wheels of the truck in turning.

Having thus fully described my invention, what I claim as new, and desire to secure by Letters Patent, is—

The combination, with the platform A, 25 mounted upon transverse bars A', secured to the side beams, A², said beams being provided with inclined notches A⁵, of the curved standards A³, having the bars B secured thereto, notched end boards, D, rods or braces E, a 30 cover, C', and frame B' B², substantially as set forth.

In testimony that I claim the foregoing as my own I have hereto affixed my signature in presence of two witnesses.

CHARLES COTTON.
